(57) **CLAIM**

The ornamental design for a vehicle, as shown and described.

DESCRIPTION

FIG. 1 is a right, perspective view of the vehicle;
FIG. 2 is a left side elevation view thereof, the right side elevation view being a mirror image thereof;
FIG. 3 is a front elevation view thereof;
FIG. 4 is a back elevation view thereof;
FIG. 5 is a top elevation view thereof; and,
FIG. 6 is a bottom elevation view thereof.

The broken lines showing a handlebar, foot rests, wheels, motorized wheel hubs, seat, internal frame components and wheel mounts, wheel-recesses, brake and other control levers, lights, joining seams, recesses, and other mechanical features form no part of the claimed design.

The broken lines adjacent to the shaded left and right side surfaces of the vehicle, except for the vertical broken lines, are boundaries and form no part of the claimed design.
